UNITED STATES PATENT OFFICE.

CHARLES BUSH, OF SCHOOLHOUSE, WEST VIRGINIA, ASSIGNOR OF ONE-HALF TO WILLIAM R. CARNAHAN, OF SCHOOLHOUSE, WEST VIRGINIA.

WIRE-STRETCHER.

SPECIFICATION forming part of Letters Patent No. 748,697, dated January 5, 1904.

Application filed April 29, 1903. Serial No. 154,770. (No model.)

To all whom it may concern:

Be it known that I, CHARLES BUSH, a citizen of the United States, residing at Schoolhouse, in the county of Jackson and State of West Virginia, have invented a certain new and useful Wire-Stretcher, of which the following is a specification, reference being had thereunto to the accompanying drawings.

This invention relates to wire-stretchers, the object in view being to provide a simple, cheap, and effective wire-stretcher of lever form embodying means for engaging a fence-post and using the same for a fulcrum about which the stretcher is operated, the wire-stretcher also embodying a knuckle-jointed gripping-head having a plurality of wire-grips which adapt the device to be used either in connection with rough, smooth, or barbed wire.

A further object of the invention is to so arrange the wire-gripping devices that they will not interfere with each other, one of the wire-grips being so connected with the gripping-head that it may be readily detached therefrom. The gripping-head is so connected pivotally with the main body of the wire-stretcher that it can swing only in a certain plane, which has the effect of steadyng the operation of the stretcher and rendering the same more reliable and rapid in use.

With the above and other objects in view the invention consists in the novel construction, combination, and arrangement of parts, as hereinafter fully described, illustrated, and claimed.

In the accompanying drawings, Figure 1 is a perspective view illustrating the wire-stretcher and the method of using the same. Fig. 2 is an enlarged plan view of the wire-stretcher, illustrating the first step in the operation of stretching a fence-wire. Fig. 3 is a similar view showing the position of the stretcher and wire after the latter has been stretched and is in readiness to be fastened to a post. Fig. 4 is an enlarged detail plan view of the wire-gripping head with one of the wire-grips removed. Fig. 5 is a detail

perspective view of one of the wire-grips detached. Fig. 6 is a plan view of the double retainer-hook.

Like reference-numerals designate corresponding parts in all the figures of the drawings.

The improved wire-stretcher contemplated in this invention comprises, essentially, a lever 1, having at one end a handle extension 2 and provided near its other end with a large gooseneck or segmental portion 3, adapted to partially embrace a post 4, the latter forming the fulcrum upon which the lever is turned in the operation of stretching a wire. The lever also comprises a heel extension 5, which is substantially parallel with the main body 1 of the lever and is connected with said main body by means of the gooseneck or segmental portion 3. Said gooseneck or segmental portion 3 is strengthened by means of a reinforcing rib or flange 6, extending along the outer side thereof, as shown.

In carrying out the present invention the wire-gripping head 7 is connected, by means of a knuckle-joint 8, with the extremity of the heel extension 5 of the lever, said knuckle-joint consisting of a plurality of interfitting and overlapping ears connected by a single pivot or bolt 9, which allows the gripping-head to swing only in the same plane with the heel extension 5, thereby keeping the wire exactly in alinement with the lever as the wire is carried across the post prior to being secured thereto.

At its extremity the gripping-head 7 is provided with a claw 10, which is used principally for obtaining a hold upon rough or barbed wire, in which event the other gripping device hereinafter described is detached. The other gripping device consists of a thumb-lever 11, provided at one end with an exteriorly roughened or serrated head 12, having oppositely-projecting trunnions or pintles 13, which are received in oblique slots 14 in a pair of oppositely-arranged lugs or ears 15, projecting from the same side of the gripping-head 7 as the claw 10 and as clearly shown

in Figs. 2 and 3. The trunnions or pintles 13 are eccentric with relation to the curvature of the head 12 of the detachable grip, so that as the lever 11 is rocked the head 12 operates to grip the fence-wire between itself and the gripping-head 7 or release said wire, as the case may be.

After the lever has been swung around the post to the position illustrated in Fig. 3 and 10 the wire has thereby been stretched across the post a staple or other suitable fastener 16 is driven across the wire and into the post. This operation is facilitated by means of a 15 retainer-hook 17, which is jointed to the handle, as shown at 18, and provided with one or more hooks 19, either of which may be engaged over the fence-wire, (shown at 20,) so as to hold the wire-stretcher as a whole in place while driving the staple or securing the 20 same to the post.

The inclined slots 14 allow the detachable grip to be removed from the gripping-head by turning the same toward the claw 10. In any other position, however, the gripping-lever 11 through the medium of the pintles 13 and inclined slots 14 is prevented from becoming accidentally disconnected from the device. In operating upon smooth wire the gripping-lever 11 is employed, the wire passing 25 between the jaws of the claw 10. In stretching rough or barbed wire, however, the lever 11 is preferably detached and the claw 10 used alone. The claw 10 and the gripping-head 12 are arranged in longitudi-

nal alinement with each other, and therefore 35 do not interfere.

Having thus described the invention, what I claim as new, and desire to secure by Letters Patent, is—

1. In a wire-stretcher, a lever provided with 40 a gooseneck for embracing a post, a heel extension at the extremity of the gooseneck, a gripping-head having a knuckle-jointed connection with said heel extension, a wire-gripping device carried by said gripping-head, 45 and an auxiliary wire-grip detachably connected with the gripping-head.

2. In a wire-stretcher, a lever provided with 50 a gooseneck, adapted to embrace a fence-post, a heel extension connected with the extremity of said gooseneck, a wire-gripping head having a knuckle-jointed connection with said extension, and adapted to swing in the same plane with said extension, a wire-gripping claw carried by said head, and an 55 auxiliary detachable wire-grip consisting of a lever provided with a gripping-head, pintles at opposite sides of the head, and lugs on the main gripping-head provided with inclined slots to receive the pintles of the auxiliary gripping device, substantially as described.

In testimony whereof I affix my signature in presence of two witnesses.

CHARLES BUSH.
